UNITED STATES PATENT OFFICE.

ROBERT CARSON, OF ETNA, PENNSYLVANIA, ASSIGNOR TO WILLIAM WILSON, OF SHARPSBURG, PENNSYLVANIA.

CUSPIDOR.

SPECIFICATION forming part of Letters Patent No. 656,939, dated August 28, 1900.

Application filed February 5, 1900. Serial No. 4,040. (No model.)

To all whom it may concern:

Be it known that I, ROBERT CARSON, a citizen of the United States of America, residing at Etna, in the county of Allegheny and State 5 of Pennsylvania, have invented certain new and useful Improvements in Cuspidors, of which the following is a specification, reference being had therein to the accompanying drawings.

10 This invention relates to certain new and useful improvements in cuspidors, and more particularly to that special class that are designed to retain their contents when upset.

One object of the invention is to construct 15 a cuspidor that will not spill when upset, irrespective of the angle or degree in which the same may be tilted.

The invention has for its further object to construct a cuspidor of the above-referred-to 20 class that may be easily reversed, the upper and lower portions of the cuspidor each being provided with a bell-shaped opening communicating with a spherical casing, the latter containing a receptacle secured therein in a 25 manner that will prevent the contents from becoming accidentally discharged therefrom in case the vessel is upset.

With the above and other objects in view 30 the invention finally consists in the novel construction, combination, and arrangement of parts to be hereinafter more fully described, and specifically pointed out in the claims.

In describing the invention in detail reference is had to the accompanying drawings, 35 forming a part of this specification, and wherein like numerals of reference indicate corresponding parts throughout the several views, in which—

Figure 1 is a side elevation of my improved 40 cuspidor. Fig. 2 is a vertical sectional view thereof. Fig. 3 is a side view of the cuspidor when upset, showing in dotted lines the position of the inner vessel. Fig. 4 is a longitudinal sectional view taken on the line 4 45 of Fig. 2.

Referring to the drawings by reference-numerals, 1 indicates a spherical casing which is preferably formed of two hemispherical parts suitably secured together.

50 The reference-numeral 2 indicates an upper bell-shaped mouth communicating with the

casing 1 and having an opening 3 in the lower portion thereof.

The reference-numeral 4 indicates a lower bell-shaped mouth, which likewise communicates with the casing 1 and has formed therein an opening 5.

Lugs 6 6 are secured centrally to the inner walls of the casing and arranged diametrically opposite each other, carrying pins 7, the latter being adapted to engage a ring 8 and form a pivotal connection therewith. The ring 8 is likewise provided with lugs 9, rigidly secured thereto upon the inner face of the ring. These lugs carry pins 10, adapted to engage the interior vessel 11 and form a pivotal connection therewith, the said inner vessel being also provided with an opening 12, the latter corresponding with the opening 3 or the opening 5, as the case may be.

The operation of my improved cuspidor is as follows: By reason of the inner vessel being partially cut away at its upper portion the lower part of the receptacle will be somewhat heavier, together with the contents it 75 may contain, and will cause the opening 12 to be in an almost upright position, irrespective of the tilting of the cuspidor. The axis 7 or 10 permits the inner vessel to turn in any direction, and when the cuspidor is reversed 80 the opening 12 will correspond with the opening 5. When it is desired to empty the contents of the cuspidor, the inner vessel is held in position by engaging the bottom thereof through the opening 5 of the bell-shaped 85 mouth 4.

The many advantages obtained by the use of my improved cuspidor will be readily apparent from the foregoing description, taken in connection with the accompanying drawings.

It will be noted that various changes may be made in the details of construction without departing from the general spirit of my invention.

Having thus fully described my invention, what I claim as new, and desire to secure by Letters Patent, is—

1. In a cuspidor, the combination of an outer casing provided with an upper and lower 100 bell-shaped mouth having openings therein communicating with said casing, an interior

ring pivotally secured in said casing, and an interior vessel pivotally connected to said ring, all parts being arranged and operating substantially as herein shown and described.

5 2. In a cuspidor, the combination of an outer casing, an inner casing having an opening secured therein, an upper and lower bell-shaped mouth communicating with said casing, and means whereby when said cuspidor
10 is reversed the opening of the inner casing

will register with the upper or lower bell-shaped mouth of the outer casing, substantially as described.

In testimony whereof I affix my signature in the presence of two witnesses.

ROBERT CARSON.
